C. Y. Haynes of Philadelphia Pa.
Letters Patent. No. 331. Dated Nov. 12. 1850.

The Schedule referred to in these Letters Patent and making part of the same.

To all whom it may concern:

Be it known that I, Charles Younglove Haynes, of the City of Philadelphia, in the County of Philadelphia, and State of Pennsylvania, have invented, and produced, a new and original design, for bas relief, and for other purposes, and I do hereby declare, that the following is a full, and exact description of the same, reference being had to the accompanying drawings, and to the letters of reference marked thereon, to wit,

On the outer edge, is five plain borders, alternately raised, and sunk, as shewn at A, in the accompanying drawings, adjoining which, is the fasces, or bundle of Rods B, representing the three great divisions of the States, the Northern, Middle and Southern, sections. Each bound together by their own fraternal ties, the whole is then represented as being bound, together by the broad band of confederation C, overlapped, and entwined, by the Oak leaf, emblematical of the durability of the Union. The four corners are composed of Shields, formed by a combination of flowers, and scroll work, in the shape of the magnetic needle, pointing to the polar star in the centre. In the centre of the four sides, are vignettes, formed by scrolls, D. E. F. G.—in the one at the top D, the Goddess of Liberty, is represented as taking in her shell shallop, a poor Orphan Boy, to conduct on the Ocean of Life, holding in her lap a wreath, and pointing to her Temple in the distance, promising him that should he be so fortunate, as to climb that summit that wreath should deck his Tomb.

That Orphan Boy has grown to manhood, and to riper years, and is hailed, as the venerated Sage of Ashland, the Hon. Henry Clay, standing on the broad platform, where he as a Statesman, and Politician, is proclaiming the principles which have ever actuated his life, holding in his hand, and delivering his farewell address to the Senate, and History perched on a pedestal, is recording on her tablet, his appeal to the Divine Arbiter, for the truth of the declaration, that he has been influenced by no impure purpose, no personal motive, has sought no personal aggrandizement, but that in all his public acts, he has had a sole, and single eye, and a warm devoted heart, directed, and dedicated, to what in his best judgment, he considered, to be the true interest of his Country, the correctness of which is sanctioned by his true autograph. — From a point behind that Vignette D, are rays of light issuing, extending far and wide, emblematic of the light that has, and still is, emanating from the career of that Orphan Boy. — In the left hand vignette E stands Justice, holding that wreath, upon the hilt of her sword, ready when that venerated form is bowed in dust, to place it upon his Tomb.

In the one on the right F, stands Fame, with her scroll, resting upon her Trumpet, ready also to make the loud proclaim, that his fame has everlasting years. On each stands the American Eagle, as a guard to see both perform their duty, and over him waves the Star Spangled Banner. The bottom vignette G, contains my own card. On the left of which Science and Young Genius H, H, are standing under the tree of Liberty, Science holding in her hand, a huge ball, ready to put it in motion, emblematic of the new power of the Galvanic Batteries, which are before her, and in other parts of the design — from above her head, at I, may be seen the small rays of light, that have commenced breaking in upon this vast, and hidden power — On the other side, standing also under the tree of Liberty, is a female J, representing the power of Steam, and Mechanical Arts. The whole is surrounded by a combination of scroll work K, terminating inwards, (and upwards for bas relief) by a flange, corresponding with the scroll work, forming a raised ornamental tablet, L, on which stands Mr. Clay, in his natural speaking attitude, as he placed himself, at my request, for an Original Daguerreotype, taken expressly for the work; behind him stands a shield M, leaning against a pedestal, on which History, is recording his acts for posterity. The magnetic needle at the corners O, and the flange pointing inwards, is intended to represent that from every section of this wide spread Republic, Mr. Clay is looked to, as a guide to happiness, peace, and prosperity.

The Stars, that are in the four sections of lattice work on the sides P, are emblematic of the vast, and countless multitude from the four corners of the globe, that are fleeing from oppression, and seeking an asylum, within the pale, of this happy, prosperous, and glorious Union.

What I claim as my design, and wish to secure by Letters Patent is, the combination of scroll work, and Vignette, which forms the ornamental Tablet, the Shield, on which History is recording the extract of Mr. Clay's address, together with the side view attitude, in which he is represented, and the ornamental tablet, on which he stands, from which copies may be taken, for sale or use, either by casting, moulding, embossing, or in any manner, or with any material whatsoever, in bas relief, or by copies to be taken, by painting, drawing, sketching, etching, engraving on wood or metal, or by any material, spread upon it; or by the Electrotype, Talbotype, or Daguerreotype process, or by ruling with machinery, or in any other manner whatsoever.
